UNITED STATES PATENT OFFICE.

CARL OSCAR ANDERSON, OF SPRINGFIELD, ILLINOIS, ASSIGNOR TO MONTGOMERY WARD & CO. INC., OF CHICAGO, ILLINOIS, A CORPORATION OF NEW YORK.

SPEED-INDICATOR FOR CENTRIFUGAL MACHINES.

1,278,088.

Specification of Letters Patent. Patented Sept. 10, 1918.

Application filed November 2, 1917. Serial No. 199,873.

To all whom it may concern:

Be it known that I, CARL OSCAR ANDERSON, a citizen of the United States, residing at Springfield, in the county of Sangamon and State of Illinois, have invented certain new and useful Improvements in Speed-Indicators for Centrifugal Machines, of which the following is a specification.

This invention has reference to timing devices or speed indicators for centrifugal separators, such as hand-power operated machines employed for the separation of cream from milk. In these machines the main factor of separation is centrifugal force, and it is important that the separators shall be run at the full rate of speed in order to remove all the cream. Furthermore, these machines usually are manipulated by unskilled persons with whom it is difficult to maintain the proper uniform speed for attaining the best results in the separation of the constituents. The speed of the machines thus will frequently vary and this results in varying degrees of separation with loss in the amount of cream obtained.

The present invention, therefore, aims to provide a simple and cheap construction by which the required speed of operation of the separator can be maintained and which will indicate, both visually and audibly, when the speed has fallen below that which is requisite for the most effectual separation of the constituents.

Having this general object in view, and others which will appear as the nature of the improvements is better understood, the invention consists substantially in the novel construction, combination and arrangement of parts hereinafter fully described, illustrated in the accompanying drawings, and pointed out in the appended claims. In the drawings—

Figure 1 is a side elevation of the crank of a centrifugal separator equipped with a speed indicator constructed in accordance with the present invention;

Fig. 2 is a face elevation thereof, the crank being broken away;

Fig. 3 is a sectional plan view on the line 3—3 of Fig. 2, showing the indicator more clearly in its assembled relation to the crank;

Fig. 4 is a face elevation of another form in which the same is designed as an attach-

ment for application to a crank without being formed as an integral part thereof;

Fig. 5 is a plan view of the construction illustrated in Fig. 4.

Referring now in detail to the accompanying drawings, the numeral 10 designates the crank of a centrifugal separating machine, such as a cream separator, which crank is provided with a loose handle sleeve 11, as is common in structures of this character. Projecting from one side of said crank 10 is a lug 12 which extends at right angles to the crank. This lug, in the form illustrated in Figs. 1, 2 and 3, is integral with the crank 10. Associated with the lug 12 is a pin 13 provided at its free end with a head 14 having a diameter greater than the diameter of said pin, and slidably mounted on said pin 13 is an annular weight 15 which is designed to move between the head 14 and the lug 12 during the rotation of the crank 10 when the speed of the latter is under that required for effecting the most advantageous separation of the cream from the milk. It will be observed that the pin 13 lies in substantially parallel relation to the crank 10, and as the crank rotates said weight will be thrown against the lug 12 by centrifugal force and remain in contact with said lug after the desired speed has been attained. But until this speed has been attained the weight 15 traverses the pin 13 and alternately strikes the head 14 and lug 12 as the handle moves to the high and low positions of its path of rotation.

Consequently, the contact of the weight 15 with the lug 12 and head 14 will emit a metallic sound characteristic of the contact of one metal with another, and whether the operator is observing the movement of the weight or not, this audible indication serves to advise the operator that the speed of rotation of the crank is under that which is requisite for the most advantageous separation of the cream from the milk. At the same time, however, the movement of the weight 15 will indicate visually the conditions just mentioned, and not until it comes to rest against the lug 12 will it be apparent to the operator that the speed properly required for the operation of the crank 10 has been obtained.

In Figs. 4 and 5 is disclosed another form of the invention. This includes the pin 13 with its head 14 and the sliding weight 15

mounted on said pin but the lug 12 is a separate element from the crank 10. To provide for attachment of the lug 12 the latter has formed thereon an eye 16, the opening of which receives the handle 17 on which a handle sleeve 18 is loosely mounted. The eye 16 is thus clamped between the crank 10 and an engaging head or nut 19 associated with the handle 17, in which position the lug 12 is maintained in proper relation to the crank 10 to preserve the parallelism of the pin 13 with said crank.

It will be obvious that the operation of the construction illustrated in Figs. 4 and 5 is similar to that of the construction illustrated in Figs. 1, 2 and 3.

The invention is susceptible of application in use to any rotating element the speed of which it is desired to indicate and 20 to maintain within predetermined limits. Therefore, in lieu of applying the indicator to the rotating crank shaft of a cream separator it may be applied to a pulley.

If desired, a bell may be substituted for 25 the weight 15.

I claim:

1. In a speed indicator of the class described, the combination with a rotatable element, of an elongated support arranged 30 at one side thereof in offset relation thereto, a continuously visible indicator associated with said support and movable thereon during operation of the rotatable element at a speed below a predetermined point, and 35 means for bringing said indicator to rest when said predetermined speed has been reached.

2. In a speed indicator of the class described, the combination with a crank, of a 40 lug associated therewith, a pin supported by said lug and arranged at one side of said crank, an element slidably mounted on said support and adapted to traverse the same under a predetermined speed of rotation of 45 said crank, and means carried by said pin and co-operating with said lug to produce sound during the traverse of said element on said pin.

3. In a speed indicator of the class de-

scribed, the combination with a crank, of a 50 lug associated therewith, a pin supported by said lug and arranged at one side of said crank, a slidable element surrounding said pin and adapted to traverse the same under a predetermined speed of rotation of said 55 crank, and means carried by said pin and co-operating with said lug to produce sound during the traverse of said element on said pin.

4. In a speed indicator of the class de- 60 scribed, the combination with a crank, of an elongated support associated with said crank, an element slidably mounted on said support and adapted to traverse the same under a predetermined speed of rotation of 65 said crank, means for limiting the movement of said element on said support when the speed of rotation of the crank is under the predetermined limit, and means for causing said element to come to rest when the pre- 70 determined limit of speed has been attained.

5. In a speed indicator of the class de- 75 scribed, the combination with a rotatable element, of a support associated therewith, an element slidably mounted on said support 80 and adapted to traverse the same under a predetermined speed of the rotatable element, and means with which said sliding element co-operates for emitting sound during the 85 traverse thereof.

6. In a speed indicator of the class de- 90 scribed, the combination with a rotating element, of a lug associated therewith, a pin supported by said lug, an element slidably mounted on said pin and adapted to traverse the same under the predetermined speed of said rotating element, and means carried by said pin and co-operating with said lug to produce sound during the traverse of said element on said pin.

In testimony whereof I have hereunto signed my name in the presence of two subscribing witnesses.

CARL OSCAR ANDERSON.
